Phillip Anderson*

UNITED STATES PATENT OFFICE.

JOHN KILBURN, OF BELMONT, MASSACHUSETTS.

SPINDLE-BEARING.

SPECIFICATION forming part of Letters Patent No. 590,320, dated September 21, 1897.

Application filed December 2, 1896. Serial No. 614,256. (No model.)

To all whom it may concern:

Be it known that I, JOHN KILBURN, a citizen of the United States, residing at Belmont, in the county of Middlesex and State of Massachusetts, have invented certain new and useful Improvements in Spindle-Bearings; and I do hereby declare the following to be a full, clear, and exact description of the invention, such as will enable others skilled in the art to which it appertains to make and use the same.

In spindles of the self-centering or "top" type, which are rotated at high speed, it has been found in practice to be desirable to have a certain amount of friction between the spindle and its bolster to insure a smooth and even running of the spindle. It has further been found to be of the greatest advantage that the amount of friction between the bolster and spindle be kept as nearly as practical constant and not increased by the wear of parts. As spindles of this type have been commonly heretofore constructed they are provided with a tapered pintle fitted to correspondingly-shaped bearings in a bolster, and it has been heretofore proposed in the art—as, for example, in the patent to Draper, No. 507,355, dated October 24, 1893—to provide a spring which supports the bolster and acts to hold it up to its fit on the spindle-pintle, but such arrangement has been heretofore, in so far as I am advised of the art, found to be impracticable, for the reason that no means has been heretofore provided whereby the tension of the spring could be regulated, the construction of the device being such that a spring must be selected and inserted therein which will give the required upward effort. It will be evident to one skilled in the art that if the bolster is forced upward with too great a pressure the spindle will turn with too great friction in its bearings and that if the bolster is not held up with sufficient force to keep it to its fit the spindle will run unevenly, and it will be also evident that to secure the required upward pressure for a successful operation of the device the elastic force exerted by the spring must be accurately determined, and when the difference in the elastic force of springs formed of the same-sized wire is taken into consideration it will

be seen that it is impractical to produce commercially springs which will give successful results. It is also to be noted that as the pintle wears away or wears into the step the spring will be further compressed and to maintain a uniform pressure upon the bolster must be adjusted to provide for the change in the relative position of parts.

The object of the present invention is to obviate the difficulties above noted and to generally improve the form and arrangement of spindle-bearings of this class, and to such end the present invention consists of the devices and combinations of devices as herein-after described and claimed.

The present invention is illustrated in the accompanying drawings, wherein—

Figure 1 shows a central vertical section through a spindle-bearing, the lower portion of the spindle and other parts being shown in elevation. Fig. 2 is a similar view of a modified form of the invention.

In the drawings, A represents the spindle, which carries the usual sleeve-whirl B and has the usual tapered end or pintle a below said whirl. C represents the bolster, having a tapered bearing, within which the pintle a is supported and is free to rotate, and which may be surrounded by any usual elastic packing c. D represents the bolster-case, and E the spindle-rail, all of which parts, except as hereinafter specified, may be of any usual or preferred form and arrangement.

F represents a pintle, which has an upper end f of polygonal shape in cross-section, or any suitable shape other than round, projected through a similarly-shaped opening e' in the bottom of the bolster C and forming a step or bearing for the end of the spindle-pintle a. The pintle F is restrained from rotation with the spindle and by its connection with the bolster C prevents the rotation of the bolster. Any suitable means may be employed to restrain the rotation of the pintle F, such as providing it with an end f' of polygonal shape in cross-section, or any suitable shape other than round, which engages a similarly-shaped recess d in the bottom of the bolster-case D.

The bolster C is free to reciprocate along the pintle F and its lower end rests upon a

coiled spring G, which surrounds the pintle F and rests upon a block H or other suitable support supported by said pintle F.

The block or support H is movable along 5 the pintle F, and means are provided whereby said block or support may be held in any required position on the pintle F so that the spring G, when the bolster C is placed thereon and the spindle placed in the bolster and rotated at the required speed, will be sufficiently compressed to exert the required upward effort to properly hold the bolster to its fit.

As shown in Fig. 1, the block H has a threaded aperture, which engages a threaded portion 15 f² of the pintle F, the block in this form having a recess h, in which is seated the lower end of the coiled spring G, and to prevent accidental turning of the block H upon the pintle F it is provided with a vertical groove h², 20 which is engaged by a pin h³, driven into the bolster-case D. As shown in Fig. 2, the pintle F' has a smooth cylindrical portion f³, and the block H' is connected thereto by a driving fit in such a manner that it may be driven to different positions along said pintle.

In practice I find that the best results are secured when the upward effort exerted by the spring G is equal to or slightly greater than the weight of the bolster C, but with my 30 improved arrangement one skilled in the art can readily and quickly adjust the spring G to secure the most successful results under any required conditions.

When the pintle a becomes so far worn or 35 so far wears into the step that the spring G is sufficiently compressed to exert too great an upward thrust, the spring G may be adjusted by moving the block H (or H') along the pintle F to provide for the change in the relative 40 position of the parts.

Having thus described my invention, I desire to say that I do not wish to limit the same to the details of construction herein shown and described; but

45 I claim as novel and desire to secure by Letters Patent of the United States—

1. The combination with a spindle and its bolster, of a spring arranged to hold the bolster to its fit on the spindle, and a vertically-

adjustable support for the spring, substantially as described.

2. The combination with a spindle and its bolster, of a step-pintle along which the bolster is free to reciprocate, and which is provided with a threaded portion, a grooved block 55 engaging the threaded portion of the pintle, and a spring interposed between the block and the bolster, substantially as described.

3. The combination with a spindle, its bolster, and bolster-case, of a step restrained from 60 rotation but free to reciprocate in the bolster, a spring supporting the bolster, and a recess in the base of the bolster engaging the step to hold the bolster from rotation, substantially as described.

4. The combination with a spindle, its bolster and bolster-case of a spring supporting the bolster, a recess formed in the base of the bolster, a recess formed in the base of the bolster-case, a step-pintle along which the 70 bolster is free to reciprocate engaging the recesses in the bolster and its case, and acting to restrain the bolster from rotation, substantially as described.

5. The combination with a spring-supported 75 bolster provided with a recess in its base, of a step along which the bolster is free to reciprocate, said step engaging a recess in the base of the bolster to prevent rotation of the bolster, substantially as described.

6. The combination with a spring-supported 80 bolster, of a loosely-held step-pintle free to tip laterally in all directions, projected into the bolster and supporting the spindle, substantially as described.

7. The combination with a bolster, of a 85 spring supporting the bolster, a loosely-held step-pintle free to tip laterally in all directions, projected into the bolster and supporting the spindle, and a support for said spring 90 carried by the pintle, substantially as described.

In testimony whereof I affix my signature in presence of two witnesses.

JOHN KILBURN.
